DESIGN FOR A HANDBAG

Frank H. Rath, Garden City, N. Y.

Application November 17, 1945, Serial No. 123,839

Term of patent 3½ years

(Cl. D87—3)

To all whom it may concern:

Be it known that I, Frank H. Rath, a citizen of the United States of America, residing in Garden City, county of Nassau, and State of New York, have invented a new, original, and ornamental Design for a Handbag, of which the following is a specification, reference being had to the accompanying drawing, forming part thereof, wherein

I claim:

The ornamental design for a handbag, substantially as shown.

FRANK H. RATH.
